UNITED STATES PATENT OFFICE.

ISAAC E. PALMER, OF MIDDLETOWN, CONNECTICUT.

DESIGN FOR A HAMMOCK-HOOK.

SPECIFICATION forming part of Design No. 23,350, dated June 12, 1894.

Application filed May 18, 1894. Serial No. 511,726. Term of patent 14 years.

To all whom it may concern:

Be it known that I, ISAAC E. PALMER, of Middletown, in the county of Middlesex and State of Connecticut, have invented and produced a new and original Design for Hammock-Supporting Hooks, of which the following is a specification, reference being had to the accompanying drawings, forming a part thereof.

The leading feature of my design is the hammock supporting hook, provided with a loop and having the point of the hook extending across the plane of the loop, as shown.

In the accompanying drawings, Figure 1 is

a top plan view. Fig. 2 is a view in side elevation and Fig. 3 is a view in end elevation.

A represents the loop, B the hook and b the point of the hook which extends across the plane of the loop. The shank of the hook, denoted by C, is depressed below the plane of the loop.

What I claim is—

The design for a hammock supporting hook, substantially as herein shown and described.

ISAAC E. PALMER.
